FRANK F. BRADSHAW, OF TOPEKA, KANSAS, ASSIGNOR OF ONE-HALF TO F. G. THOMAS,
OF TOPEKA, KANSAS.

COLLAPSIBLE PACKING-CASE.

1,026,379.

Specification of Letters Patent.

Patented May 14, 1912.

Application filed October 6, 1911. Serial No. 653,093.

To all whom it may concern:

Be it known that I, FRANK F. BRADSHAW, a citizen of the United States, residing at Topeka, in the county of Shawnee and State 5 of Kansas, have invented a certain new and useful Improvement in Collapsible Packing-Cases, of which the following is a specification.

My invention relates to improvements in 10 collapsible packing cases.

The object of my invention is to provide a collapsible packing case which when expanded for use shall have great strength and rigidity, and which when collapsed will 15 be securely held in compact collapsed condition.

Other novel features of my invention are hereinafter fully described and claimed.

In the accompanying drawings which 20 illustrate my invention in its preferred form, Figure 1 is a perspective view of my improved packing case shown in the expanded and locked condition. Fig. 2 is a perspective view of the packing case in the 25 collapsed locked position. Fig. 3 is a top view of the body, the expanded form being shown by solid lines, and the collapsed form being represented by solid and dotted lines. Fig. 4 is a vertical cross section of the packing case when expanded. Fig. 5 is a vertical cross section of the packing case shown 30 in the collapsed condition.

Similar reference characters designate 35 similar parts throughout the different views.

The body consists of two side members 1 the ends of which are hinged to the ends of end members 2 by vertical pintles 3 which extend through interlocking tenons 4 of adjacent members.

In order to impart the greatest rigidity 40 to the case, each side member 1 is provided at one end with a right angled portion 5 which extends toward the opposite side member. The lower edges of the side members 1 are provided with longitudinal inwardly projecting cleats 6. Similar cleats 7 are provided at the lower edges of the end members 2. A removable member 8, preferably rectangular, is adapted to rest upon 45 the cleats 6 and 7 and serve as a bottom member of the case and to retain the case in the expanded rectangular form, as shown in Fig. 4.

9 designates the top member or cover 50 which is of the same form and size as the

bottom member 8 and which is provided on its upper side with one or more transverse cleats 10 which extend laterally over and are adapted to rest upon the upper edges of the members 1. In the drawings I have 60 shown the top member 9 provided with two cleats 10. The top member 9 like the bottom member 8 is adapted to be removably fitted between the body members 1 and 2, as shown in Figs. 1 and 4. It thus serves 65 not only as a cover but it helps to retain the case in the expanded form. Suitable means may be provided for releasably locking the top member 9 to the body. In the drawings I have illustrated a preferred form for 70 effecting this function. In the upper edge of each side member 1 are mounted two pairs of eyes 11. The cleats 10 are mounted respectively between the eyes of opposite pairs, as shown in Fig. 1. Resilient U 75 shaped clips 12 have their transverse portions extending across the cleats 10 and have their arms extending respectively through the adjacent eyes 11. Opposite edges of the cleats 10 are provided with recesses 13 in which are respectively mounted the inwardly turned ends of the clips 12 with which said clips are provided. The inner sides of the side members 1 are provided 80 with vertical grooves 14 in which is removably mounted a partition member 14', which serves to divide the case into two compartments and to retain the bottom member 8 upon the cleats 6 and 7. To increase the strength of the hinge connections 85 between the side and end members, the tenons 4 may be bound with metal strips 15. To collapse the packing case, the arms of the clips 12 are sprung out of the recesses 90 95 13, after which the clips are withdrawn from the eyes 11. The top member 9, partition member 14' and bottom member 8 are then removed, after which the side and end members are swung to the positions shown in solid and dotted lines in Fig. 3, in which position the cleats 6 will be edge to edge. The top, bottom and partition members are then placed between the side members 1, as shown in Figs. 2 and 5, after 100 which the clips 12 are slipped over the upper edges of the side members 1, the inwardly turned ends of the clips being slipped into recesses 16 which are provided in the outer sides of the members 1. The clips 12 in 105 110 this position serve not only to hold the

packing case collapsed, but they serve to retain therein the top member 9, the bottom member 8 and the partition member 14'.

My invention may be applied to a number 5 of uses, but it is particularly adapted for use as a shipping case for eggs. The top member 9 and bottom member 8, when the case is expanded, being located between the body members 1 and 2 give great strength 10 and rigidity to the structure.

I do not limit my invention to the structure shown and described as many modifications, within the scope of the appended claims, may be made without departing 15 from the spirit of my invention.

Having thus described my invention, what I claim and desire to secure by Letters Patent, is:

1. A collapsible packing case, having a 20 body comprising two side members and two end members, two pairs of eyes mounted respectively in two oppositely disposed members of the body, a top member adapted to be removably fitted between the body members and having two laterally extending 25 portions disposed respectively between said pairs of eyes, and two locking devices adapted to extend respectively across said two laterally extending portions and through 30 said two pairs of eyes for releasably locking the top member to the body.

2. A collapsible packing case having a body comprising two side members and two end members, two pairs of eyes mounted respectively in two oppositely disposed members of the body, a top member adapted to be removably fitted between the body members and having a cleat which is adapted to rest upon said two oppositely disposed members and between said pairs of eyes opposite edges of the cleat having recesses, and two 40 U shaped clips having inwardly extending ends and adapted to be removably mounted in said pairs of eyes respectively and when 45 in the said positions respectively extending across said cleat and having their inwardly turned ends extending respectively into said recesses.

3. A collapsible packing case having a 50 body comprising two side members and two end members hinged at their ends to the ends of the side members whereby the body may be collapsed or expanded, a top member adapted to be removably fitted between 55 the body members for holding the body expanded, and means including a U shaped clip for locking the top member to the body when the body is expanded, the clip being adapted to embrace the body at opposite 60 sides thereof to hold the body collapsed.

4. A collapsible packing case having a body comprising two side members and two end members hinged to the side members at their ends whereby the body may be expanded or collapsed, the outer sides of two 65

oppositely disposed members of the body having recesses, a top member adapted to be removably fitted between the body members for holding the body expanded, the top member having a cleat adapted to rest upon the upper edge of the body, opposite edges of the cleat having recesses, two pairs of eyes in the body and disposed at opposite sides of the cleat, and two U shaped clips having inwardly turned ends and adapted 70 to be mounted respectively in said two pairs of eyes and to extend across said cleat to hold the top member releasably on the body and in said positions having their inwardly turned ends disposed respectively in the recesses in the cleat, said clips being adapted 75 to embrace said two oppositely disposed body members when the body is collapsed, the clips in the last named positions having their inwardly turned ends disposed in the 80 recesses of said oppositely disposed members, whereby the body is held collapsed.

5. A collapsible packing case having a body comprising two side members and two end members hinged at their ends to the 90 ends of the side members, whereby the body may be expanded or collapsed, a top member adapted to be removably fitted between the body members for holding the body expanded, the top member having a cleat 95 adapted to rest upon the upper edge of the body, and means including two U shaped clips for releasably holding the cleat to the body.

6. A collapsible packing case having a 100 body comprising two side members and two end members hinged at their ends to the ends of the side members, whereby the body may be expanded or collapsed, a top member adapted to be removably fitted between 105 the body members for holding the body expanded, the top member having a cleat adapted to rest upon the upper edge of the body, and means including two U shaped clips for releasably locking the cleat to the 110 body, said clips being removable and adapted to embrace opposite sides of the body when the body is collapsed for retaining the body collapsed.

7. A collapsible packing case having a 115 body comprising two side members and two end members hinged at their ends to the ends of the side members, whereby the body may be expanded or collapsed, two oppositely disposed members of the body having inwardly extending cleats, a bottom member and a top member adapted to be removably fitted between the body members for holding the body expanded, the bottom member resting upon said cleats, the top 120 member having a cleat which extends across the upper edge of the body, and releasable means for engaging the cleat of the top member for locking the top member to the body.

8. A collapsible packing case having a body comprising two side members and two end members hinged at their ends to the ends of the side members, whereby the body
5 may be expanded or collapsed, two oppositely disposed members of the body having inwardly extending portions, a bottom member and a top member adapted to be removably fitted between the body members
10 for holding the body expanded, the bottom member resting upon said inwardly extending portions, the top member having a cleat which rests upon the upper edge of the body, two U shaped clips for extending
15 across and releasably engaging said cleat, and means for releasably securing said clips to the body.
9. A collapsible packing case having a body comprising side and end members, two
20 pairs of eyes mounted respectively in oppo-
- sitely disposed members of the body, a top member adapted to be removably fitted between the body members and having a cleat adapted to rest upon the upper edge of the body, the opposite edges of the cleat having 25 recesses, and two resilient U shaped clips each having inwardly extended ends and adapted to be respectively removably mounted in said two pairs of eyes and to extend across said cleat, and when so mounted having their inwardly extending ends mounted in said recesses respectively.
- In testimony whereof I have signed my name to this specification in presence of two subscribing witnesses.
- FRANK F. BRADSHAW.
